UNITED STATES PATENT OFFICE

2,491,298

CASE STACKER

Ermin B. Carter, Decatur, Ill.

Application April 24, 1946, Serial No. 664,578

9 Claims. (Cl. 214—6)

1

This invention relates to improvements in apparatus for stacking cases, and is more particularly concerned with the provision of an apparatus adapted for use in stacking cases of the type provided with hand-receiving apertures in the end walls thereof. More particularly, this invention comprises a pair of endless chains provided with a plurality of case lifting bars disposed for movement into the hand-receiving apertures of the cases to carry same from a loading position to a stacking position.

This invention further contemplates the provision of a case stacking apparatus embodying means for automatically moving the case lifting bars into the hand-receiving apertures of cases at the loading position of the apparatus.

This invention further contemplates the provision of a case stacking apparatus embodying resilient means for automatically retracting the lifting bars from their engagement within the hand-receiving apertures of cases when same are brought to rest in superimposed stacked relation.

This invention further contemplates the provision of an improved form of case lifting bar which is particularly adapted for use with a sprocket chain of the roller type.

It is a further object of this invention to provide a case stacking apparatus which is relatively inexpensive in construction, simple in operation and which will not readily get out of order.

This invention embodies other novel features, details of construction and arrangement of parts which are hereinafter set forth in the specification and claims and illustrated in the accompanying drawings wherein:

Fig. 1 is a front elevational view showing a case stacking apparatus embodying features of this invention.

Fig. 2 is a sectional view taken along the line 2—2 of Fig. 1.

Fig. 3 is a plan view showing the case stacking apparatus.

Fig. 4 is a detailed plan view showing one of the case lifting bars employed for movement into and out of engagement with a case.

Fig. 5 is a side elevational view of same.

Referring now to the drawings for a better understanding of this invention, the case stacking apparatus is shown as comprising a base plate 6 secured upon a pair of I-beams 1. Extending upwardly from the plate 6 is provided a pair of channel members 8 and 9 which are disposed and secured in spaced parallel relation by means of a transverse channel member 11 and brace members 12 and 13. Sprocket bearing supports 14 and 15 are secured to the upper ends of the channel members 8 and 9 to support sprocket bearings 16 at the ends thereof. A sprocket 17 is journaled on each sprocket bearing 16.

A driving shaft 18 is journaled in bearings 19

2

secured to the base plate 6 and has a pair of driving sprockets 21 secured thereto for driving engagement with their respective endless sprocket chains 22 and 23. An idler sprocket shaft 24 is journaled in suitable bearings (not shown) provided on the base plate 6 to support a pair of idler sprockets 26.

The endless chains 22 and 23 are driven by means of an electric motor 27 which is operatively connected to a gear reduction box 28 through a suitable sprocket and chain drive 29. The gear reduction box 28 drives the driving shaft 18 through a pair of sprockets 31 and 32 and sprocket chain 33.

The frame of the machine also embodies case guiding rails 34 and 36 which are preferably formed of angle iron and extend upwardly from the base plate 6 and laterally at 37. The guide members 34 and 36 are secured in parallel spaced relation by means of transverse connecting members 38, and are also secured at their lower ends to the base plate 6 and to the channel members 8 and 9 at 41. A case loading platform, which is generally indicated at 42, comprises a pair of horizontally disposed supporting members 43 and 44 having their inner ends secured to the guide rails 34 and 36, respectively, and their intermediate portions supported upon vertically disposed members 46 and 47. The vertical members 46 and 47 are also secured to the guide rails 34 and 36 by means of cross members 48 and 49.

The cases to be stacked are indicated at 50, and are of the type having hand receiving apertures 51 formed in the end walls 52 thereof. Each case 50 is lifted from its position upon the loading platform 42 by means of lifting rods 53 provided at spaced intervals on the endless chains 22 and 23. Each lifting rod 53 extends through the pin apertures 54 of a set of chain links 56 and 57 to connect same together, and to also serve as a journal for a roller 58. The outer end of each lifting rod 53 is journaled in a pair of supporting brackets 59 and 61 which, in turn, are secured on adjacent link connecting pins 62 and 63, respectively. Each lifting rod 53 is normally held in its retracted position, as illustrated in Fig. 4, by means of a compression spring 64 interposed between a collar 66, secured to the lifting rod 53, and one side of the endless chain. Each lifting rod 53 is also provided with a head portion 67 which serves as a journal for an adapter 68.

The adapter 68 is held against axial movement relative to the lifting rod 53 by means of a shoulder 69 and an annular washer 71, the washer being secured on the inner end of the lifting rod 53 by means of a screw 72 threaded into the end of the lifting rod. The adapter 68 is provided with a pair of tapered fingers 73 adapted for insertion within a hand-receiving aperture 51 of a case to prevent lateral displacement of the latter during

its travel from a loading position to a stacking position. The adapter is also provided with a bearing portion 74 for insertion within a hand-receiving aperture 51 of a case, and is preferably formed with a sharp edge 76 on its upper side for engagement against the upper wall of a case aperture 51. In order to dispose the adapter 68 in proper position for engagement within an aperture 51 of a case at the loading position 42, the adapter is provided with a weighted portion 77 which serves to maintain the fingers 73 in horizontal alignment with the apertures 51.

A pair of rod actuating arms 81 and 82 are pivotally connected at their lower ends to brackets 83 and 84, respectively, which, in turn, are secured to the upright members 46 and 47, respectively. The upper ends of the arms 81 and 82 are pulled inwardly toward each other by means of a pair of tension springs 86. It will thus be noted that the arms 81 and 82 normally act to press the lifting rods 53 inwardly for lifting engagement within the hand receiving apertures 51 of a case 50 mounted on the loading platform 42. However, during upward movement of the lifting rods 53, the inner ends of the lifting rods are disposed against their respective stop bars 87 and 88 which are secured in fixed position to the outer sides of the case supporting members 43 and 44, respectively. It will be also noted that the upper ends of the stop bars 87 and 88 terminate below the hand-receiving apertures 51 of a case 50 positioned upon the loading platform 42. The actuating arms 81 and 82 thus act to move their respective lifting rods 53 inwardly after the inner ends of the latter have passed upwardly past the upper ends of the stop arms 87 and 88. After the lifting rods 53 have been moved inwardly by the arms 81 and 82 to position their adapters 68 within the hand-receiving apertures 51, it will be noted that the washers 71 become engaged against the inner wall of the case 50 to prevent outward movement of the lifting rods 53 until the case has been brought to rest in stacked relation upon another case, at which time further downward movement of the lifting rods 53 causes the washers 71 to become disengaged from the wall of the case and permits the compression springs 64 to act to return the lifting rods 53 to their outer retracted positions.

A pair of angle-shaped stop members 91 are pivotally mounted at 92 upon a cross member 93 having its ends secured to the underside of the case supporting members 43 and 44. The vertically disposed leg 94 of each stop member 91 extends upwardly above the upper edge of a case mounted upon the loading platform 42, while the horizontally disposed leg 96 extends slightly beyond the outer side of the case and is provided with an upturned finger portion 97. When a case 50 is moved inwardly along the loading platform 42 and into engagement with the guide rails 34 and 36, it will be noted that the stop members 91 will be pivoted to move their respective stop fingers 97 into position to prevent the movement of a second case inwardly along the loading platform 42 before the prior case has moved upwardly beyond the upper ends of the vertically disposed legs 94.

In the operation of the apparatus shown and described, a case 50 to be stacked is mounted on the supporting members 43 and 44 of the loading platform 42 and then pushed inwardly until it is brought into contact against the track members 34 and 36. When a case is thus positioned, the angle-shaped stop members 91 are disposed in

the position illustrated in Fig. 2, with the stop fingers 97 moved upwardly to prevent inward movement of a second case before the first case has moved upwardly beyond the upper ends of the vertical portions 94 of the stop members 91.

After a case has been positioned upon the loading platform 42 in the manner heretofore described, the lifting rods 53 are caused to move inwardly by the action of the actuating arms 81 and 82 to engage the adapters 68 within the hand-receiving openings 51 of the case. The endless belts 22 and 23 continue their movement in a clockwise direction, as illustrated in Fig. 2, to convey the case upwardly, thence laterally and thence downwardly into stacked relation with other cases 50. During the travel of the cases between the loading position and the stacking position, the lifting rods 53 are maintained in engagement within the hand-receiving apertures 51 by means of the washers 71 disposed in engagement with the inner walls of the case. When a case is brought to rest in stacked relation, as illustrated in Fig. 2, further downward movement of the lifting rods 53 causes the washers 71 to be moved out of engagement with the inner wall of the case and thus permits the compression spring 64 to move the lifting rods 53 rearwardly to their normal retracted position.

While this invention has been shown in but one form, it is obvious to those skilled in the art that it is not so limited but is susceptible of various changes and modification without departing from the spirit and scope of the claimed invention.

I claim as my invention:

1. In an apparatus for stacking cases having apertures formed in their end walls, a frame, two sets of sprockets journaled on said frame, an endless sprocket chain mounted on each set of sprockets for conveying a case from a loading position to a stacking position, means for driving said endless chains in unison, case engaging means provided on each endless chain for detachable engagement within the apertures of a case, means for moving said case engaging means into lifting position within the apertures of a case, a pair of stop members to prevent movement of said case engaging means into lifting position within the apertures of a case prior to registry of said case engaging means with the apertures of a case disposed in the loading position, and resilient means for moving said case engaging means out of the apertures of a case when the latter is brought to rest in stacked position.

2. In an apparatus for stacking cases having apertures formed in their end walls, a frame, two sets of sprockets journaled on said frame, an endless sprocket chain mounted on each set of sprockets for conveying a case from a loading position to a stacking position, means for driving said endless chains in unison, case engaging means provided on each endless chain for detachable engagement within the apertures of a case, means for moving said case engaging means into lifting position within the apertures of a case, a pair of stop members to prevent movement of said case engaging means into lifting position within the apertures of a case prior to registry of said case engaging means with the apertures of a case disposed in the loading position, resilient means for moving said case engaging means out of the apertures of a case when the latter is brought to rest in stacked position, and track means for guiding said cases upwardly

from the loading position and downwardly into stacked position.

3. In an apparatus for stacking cases having hand-receiving apertures formed therein, a pair of endless chains for conveying cases from a loading position to a stacking position, lifting rods provided on said chains, means for moving said lifting rods axially into lifting engagement within the apertures of said cases, a pair of stop members to prevent inward axial movement of said rods prior to registry of said rods with the apertures of a case disposed in the loading position, means for retaining said lifting rods within said case apertures during movement of the cases from the loading position to stacking position, and means for returning said lifting rods to their retracted position when cases are brought to rest in stacked relation.

4. In an apparatus for stacking cases having hand-receiving apertures formed therein, a pair of endless chains for conveying cases from a loading position to a stacking position, lifting rods provided on said chains, means for moving said lifting rods axially into lifting engagement within the apertures of said cases, a pair of stop members to prevent inward axial movement of said rods prior to registry of said rods with the apertures of a case disposed in the loading position, means for retaining said lifting rods within said case apertures during movement of the cases from the loading position to stacking position, and resilient means for automatically returning said lifting rods to their retracted position when cases are brought to rest in stacked relation.

5. In an apparatus for stacking cases having hand-receiving apertures formed therein, a pair of endless chains for conveying cases from a loading position to a stacking position, lifting rods mounted on said chains for movement transversely thereof, a pair of actuating arms for moving said lifting rods axially into lifting engagement within the apertures of said cases, a pair of stop members to prevent inward axial movement of said rods prior to registry of said rods with the apertures of a case disposed in the loading position, means for retaining said lifting rods within said case apertures during movement of the cases from a loading position to a stacking position, and spring means for automatically returning said lifting rods to their retracted position when cases are brought to rest in stacked relation.

6. In an apparatus for stacking cases having hand-receiving apertures formed therein, a frame, a pair of endless chains mounted on said frame for conveying cases from a loading position to a stacking position, lifting rods mounted on said chains for movement transversely thereof, a pair of actuating arms for moving said lifting rods axially into lifting engagement within the apertures of said cases, a pair of stop members for resisting inward axial movement of said rods prior to registry of the latter with the apertures of a case disposed in the loading position, means for retaining said lifting rods within said case apertures during movement of the cases from the loading position to the stacking position, and helical compression springs mounted on said lifting rods for automatically returning the rods to their outer retracted position when cases are brought to rest in stacked relation.

7. In an apparatus for stacking cases having hand-receiving apertures formed therein, the combination with a pair of endless roller chains for conveying cases from a loading position to a stacking position, said endless roller chains including sets of inner and outer links connected together by studs with a roller journaled upon each stud, of a lifting rod mounted for axial movement through the stud openings of opposite sets of links, lifting rod supporting brackets having their outer ends journaled on said lifting rod, and their inner ends secured to adjacent link connecting studs, an adapter journaled on the inner end of the lifting rod for engagement within a case aperture, and a helical compression spring mounted on said lifting rod for yieldably resisting inward axial movement of said lifting rod.

8. In an apparatus for stacking cases having hand-receiving apertures formed therein, the combination with a pair of endless roller chains for conveying cases from a loading position to a stacking position, said endless roller chains including sets of inner and outer links connected together by studs with a roller journaled upon each stud, of a lifting rod mounted for axial movement through the stud openings of opposite sets of links, lifting rod supporting brackets having their outer ends journaled on said lifting rod, and their inner ends secured to adjacent link connecting studs, an adapter journaled on the inner end of the lifting rod for engagement within a case aperture, a helical compression spring mounted on said lifting rod for yieldably resisting inward axial movement of said lifting rod, and means provided on the inner end of said lifting rod for engagement with the inner wall of a case to be stacked.

9. In an apparatus for stacking cases having hand-receiving apertures formed therein, the combination with a pair of endless roller chains for conveying cases from a loading position to a stacking position, said endless roller chains including sets of inner and outer links connected together by studs with a roller journaled upon each stud, of a lifting rod mounted for axial movement through the stud openings of opposite sets of links, lifting rod supporting brackets having their outer ends journaled on said lifting rod, and their inner ends secured to adjacent link connecting studs, an adapter journaled on the inner end of the lifting rod for engagement within a case aperture, a helical compression spring mounted on said lifting rod for yieldably resisting inward axial movement of said lifting rod, means provided on the inner end of said lifting rod for engagement with the inner wall of a case to be stacked, a pair of case engaging fingers formed on said adapter on opposite sides of said lifting rod, and a weighted portion formed on said adapter for maintaining said case engaging fingers in a horizontal plane.
